UNITED STATES PATENT OFFICE.

JOHN B. WHITNEY, OF NEW YORK, N. Y.

DESIGN FOR DOOR-KNOBS.

Specification forming part of Design No. 6,363, dated January 21, 1873.

To all whom it may concern:

Be it known that I, JOHN B. WHITNEY, of the city, county, and State of New York, have invented a new and original Design for a Door-Knob, of which the following is a specification:

The accompanying engraving fully represents my new design.

This invention relates to a new ornamentation of the face, rim, and base of a metallic door-knob.

The main ornament on the face consists of a continuous scroll, forming six (more or less) radiating loops about a six (more or less) sided center containing a rosette. Between every pair of loops is a spear-head-shaped ornament

as shown. The edge or rim of the knob consists of curvilinear triangles within V-shaped borders, while the base of the knob is ornamented with intertwining scrolls, as shown.

I claim as my invention—

1. The design for the ornamentation of the face of the door-knob, as shown.
2. The design for the ornamentation of the edge or rim of a door-knob, as shown.
3. The design for the ornamentation of the base of a door-knob, as shown.

JOHN B. WHITNEY.
